[57] CLAIM

The ornamental design for an apron for casegoods, as shown and described.

DESCRIPTION

FIG. 1 is a left side perspective view of an apron for casegood showing my new design, the right side being a mirror image thereof;

FIG. 2 is a front elevational view thereof;

FIG. 3 is a left side perspective view of a second embodiment of the apron for casegood shown in FIG. 1, the right side being a mirror image thereof;

FIG. 4 is a right side perspective view of a third embodiment of the apron for casegood shown in FIG. 1, the left side being a mirror image thereof;

FIG. 5 is a left side perspective view of a fourth embodiment of the apron for casegood shown in FIG. 1, the right side being a mirror image thereof; and,

FIG. 6 is a left side perspective view of FIG. 5 on a different casegood, the right side being a mirror image thereof.

The broken lines shown throughout the views are for illustrative purposes only.

The surfaces or portions of the article not shown in the drawing or described in the specification form no part of the claimed design.
